UNITED STATES PATENT OFFICE

FELIX J. RUSH, OF SPARKILL, NEW YORK

DESIGN FOR A PICTURE FRAME OR SIMILAR ARTICLE

Application filed February 26, 1932. Serial No. 43,011. Term of patent 3½ years.

To all whom it may concern:

Be it known that I, FELIX J. RUSH, a citizen of the United States, residing in Sparkill, in the county of Rockland and State of New York, have invented a certain new, original, and useful Design for Picture Frames or Similar Articles, of which the following is a specification, reference being had to the accompanying drawings, forming a part thereof, and of which Figure 1 is a view in front elevation; Fig. 2 is a view in side elevation, and Fig. 3 is a view in vertical section on the line 3—3 of Fig. 1, showing my new design.

I claim:

The ornamental design for a picture frame or similar article substantially as shown.

FELIX J. RUSH.
